JOINT CLOSURE

Paul M. Gilfillan, Mount Vernon, Ohio, assignor to
Shellmar Products Company, Mount Vernon,
Ohio, a corporation of Delaware

Application October 23, 1942, Serial No. 463,053

2 Claims. (Cl. 229—48)

This invention relates to the manufacture of containers. More particularly, it pertains to improvements in a joint closure or seam construction which is moisture-vapor impervious at least to the same extent as remaining portions of the container and the provision of such a joint closure is a principal object of the invention.

More specifically, an object of the invention is the provision of a joint closure for fibrous containers in which container walls can be united at a high rate of speed by using a quick-setting glue marginally applied to one end section of a container blank, and a line of micro-crystalline wax or similar substance disposed adjacent thereto to provide a dam or moisture-vapor proof barrier when an opposing end section is brought into sealed relationship with the end section containing the wax and glue to form a permanent joint closure.

Other objects of the invention will in part be obvious and will in part appear hereinafter.

The invention accordingly comprises an article possessing the features, properties, and the relation of components which will be exemplified in the article hereinafter described and the scope of the application of which will be indicated in the claims.

For a fuller understanding of the nature and objects of the invention, reference should be had to the following detailed description taken in connection with the accompanying drawing, in which:

Fig. 1 is a perspective view of a blank of container material with a central section removed illustrating one arrangement of an application of marginal and adjacent lines of adhesive and wax;

Fig. 2 is a perspective view illustrating the blank in Fig. 1 rolled into cylindrical form and adhesively affixed together in overlapping relationship to form a moisture-vapor transmission proof joint closure; and

Fig. 3 is a diagrammatic enlargement depicting an overlapping seam construction such as that shown in Fig. 2.

Referring more particularly to the drawing there is indicated generally at 10 a blank, for example, of suitable fibrous material, such as cardboard or the like, of substantial thickness to be formed into a container. Such a blank or series of blanks prior to being cut, or while still in web form and unwinding from a mill roll, can be run through any suitable straight line gluing machine marginally to receive a stripe of quick-setting adhesive 11. This adhesive may be either an animal or other suitable quick-setting glue and pref-

erably is disposed marginally along the edge of the blank 10 or inwardly thereof a suitable distance. Simultaneously with the application of this line of adhesive or immediately thereafter another stripe of material 12 is applied to the blank lying closely adjacent said quick-setting adhesive. This material preferably is an amorphous wax composition of a micro-crystalline character. Such composition preferably constitutes about 55 to 65 per cent pure wax and the remainder of the composition consists of other desirable materials. For example, to a pure wax may be added rosin of about 20 to 30 per cent and this lends a desirable tackiness or stickiness to the final product providing adhesive as well as hardening qualities. There also may be incorporated in the composition petrolatum 5 per cent and butyl stearate 5 per cent and each of these will act as suitable plasticizers. While such a composition may have adhesive characteristics, it is not essential that these be relied on since the quick-setting glue or adhesive will be of such character as to be amply sufficient to bind together the joint closure sections in the formation of a container.

After these stripes of material have been applied to the blank, the latter is formed into any desired configuration so that opposite edges thereof are brought into a desired relationship and by the application of a suitable amount of pressure the glue will firmly and permanently secure the sections together to form a joint closure. It has been found that while an ideally permanent joint closure can suitably be formed by the use of a quick-setting adhesive, certain gas-impervious or moisture-vapor proof characteristics thereof are lacking. For example, the container blanks themselves are designed to be gas-impervious as well as immune to moisture-vapor transmission throughout the wall structure. This may be accomplished by the application overall to the blank of any suitable material which will perform these functions. "Glassine," cellulose acetate, moisture-proof Cellophane, or any other suitable moisture-proof or gas-impervious medium, such as wax, can be used. However, known glues which are capable of binding together opposite end sections to form joint closures for a container are lacking in these desirable qualities. However, the separate or simultaneous application of an amorphous wax of the character described performs the desired function and is ideally suited to the construction of such containers. Wherever a seam is necessary, whether the container be cylindrical, bag, or box-like in

contour, such a micro-crystalline wax can be applied in the manner set forth. With such a barrier the contents of the container, whether they be in liquid or gaseous form, are prevented from escaping. Likewise, gases or liquids exteriorly of the container are prevented from entering the same because of such a barrier.

It will be apparent that under certain circumstances it might be desirable to interchange the position of the quick-setting adhesive and the wax so that the latter is outwardly disposed marginally along one edge of a container joint closure section and the glue inwardly disposed adjacent the wax barrier. The glue can also be applied so as to leave room adjacent each side thereof for the application of the wax barrier when circumstances require such an application. In this manner, an ideal container of any suitable material can be constructed with a joint closure which combines a moisture-vapor proof barrier with the best physical strength characteristics of a combining quick-setting glue.

It will thus be seen that the objects hereinbefore set forth may readily and efficiently be attained and since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and

specific features of the invention herein described, and all statements of the scope of the invention which, as a matter of language, might be said to fall therebetween.

Having described my invention, what I claim as new and desire to secure by Letters Patent is:

3. In a container, the improvement comprising a blank of container material having along one marginal edge on one surface thereof adjacently disposed stripes of a thermosetting glue and an amorphous wax, said blank being formed into a container wall structure with an opposite marginal edge on the other surface thereof overlying said stripes of glue and wax and forming a joint closure seam for the wall of said container, said glue securing said blank structure into said container wall formation and said wax being a barrier layer against moisture-vapor transmission between said joint closure and said glue.
10. 1. In a container, the improvement comprising a blank of container material having along one marginal edge on one surface thereof adjacently disposed stripes of a thermosetting glue and an amorphous wax, said blank being formed into a container wall structure with an opposite marginal edge on the other surface thereof overlying said stripes of glue and wax and forming a joint closure seam for the wall of said container, said glue securing said blank structure into said container wall formation and said wax being a barrier layer against moisture-vapor transmission between said joint closure and said glue.
15. 2. In a container, a joint closure which comprises in combination, container wall sections secured together by means of a thermo-setting adhesive marginally disposed between said sections, and at least one moisture-vapor proof barrier consisting of a micro-crystalline wax composition disposed between said joint sections and lying inwardly of said thermo-setting adhesive, said composition containing pure wax which constitutes about 55 to 65 per cent of said composition, and said wall section being formed from a blank having said adhesive and wax marginally applied adjacent each other on the same surface of said blank.
20. 2. In a container, a joint closure which comprises in combination, container wall sections secured together by means of a thermo-setting adhesive marginally disposed between said sections, and at least one moisture-vapor proof barrier consisting of a micro-crystalline wax composition disposed between said joint sections and lying inwardly of said thermo-setting adhesive, said composition containing pure wax which constitutes about 55 to 65 per cent of said composition, and said wall section being formed from a blank having said adhesive and wax marginally applied adjacent each other on the same surface of said blank.
25. 2. In a container, a joint closure which comprises in combination, container wall sections secured together by means of a thermo-setting adhesive marginally disposed between said sections, and at least one moisture-vapor proof barrier consisting of a micro-crystalline wax composition disposed between said joint sections and lying inwardly of said thermo-setting adhesive, said composition containing pure wax which constitutes about 55 to 65 per cent of said composition, and said wall section being formed from a blank having said adhesive and wax marginally applied adjacent each other on the same surface of said blank.

PAUL M. GILFILLAN.
